SUCTION CLEANER AGITATOR

Harry B. White, Canton, Ohio, assignor to The Hoover Company, North Canton, Ohio, a corporation of Ohio

Application October 26, 1935, Serial No. 46,855

12 Claims. (Cl. 15—183)

The present invention relates to suction cleaners in general and particularly to new and novel improvements in suction cleaner agitators. More specifically the invention comprises a new and improved removable brush for a rotary agitator in a suction cleaner.

It is an object of the present invention to provide a new and improved agitator for a suction cleaner. It is another object of the invention to provide a new and improved rotary agitator for a suction cleaner. A still further object is to provide a new and improved removable brush for a rotary agitator in a suction cleaner. A still further object is the provision of a removable brush for a suction cleaner rotary agitator which brush includes resilient means to position it in place. These and other more specific objects will appear upon reading the following specification and claims and upon considering in connection therewith the attached drawing to which they relate.

Referring now to the annexed drawing, in which a preferred embodiment of the invention is disclosed:

Figure 1 is a front view of a suction cleaner embodying a rotary agitator in which is embodied a removable brush constructed in accordance with the present invention;

Figure 2 is an enlarged side view of a part of the rotary agitator with certain portions of the agitator broken away to show the removable brush positioned therein;

Figure 3 is an enlarged section of one end of the removable brush showing the rubber pad displaced from its seat;

Figure 4 is a view in perspective of a brush constructed in accordance with the present invention, and

Figure 5 is a partial section through the brush and agitator body upon the line 5—5 of Figure 2. In the drawing, and in Figure 1 in particular, a modern suction cleaner is disclosed which comprises a nozzle 1, a fan chamber 2 which houses a suction-creating fan 3, and a casing 4 within which is positioned an unshown motor which functions in the operation of the machine to drive the fan 3. The motor shaft 5 extends downwardly through the fan chamber 2 and is connected by a power-transmitting belt 6 to a rotary agitator 7 positioned within the cleaner nozzle. Agitator 7 comprises a cylindrical body which is rotatably supported upon a through supporting shaft 8 and which is provided with rigid beater elements 9 upon its surface and with brush seats 10 within which are positioned removable brush elements. The cleaner is removably mounted upon support-

ing wheels 11 and a pivoted handle 12 is provided by which the cleaner operator may propel the machine over the supporting surface.

The removable brush for the agitator 7 comprises an elongated back 15 throughout the greater part of the length of which flexible bristles 16 are mounted extending at one side. Brush back 15 is rigid and preferably of metal and is provided at one end with a downwardly and outwardly sloping face 17 in which is positioned a recessed seat 18 which may be of any shape but is preferably square or rectangular and in which is mounted a resilient pad 19. Pad 19 is preferably of rubber but may be of any material which is resilient and which does not harden appreciably with age. The opposite end of brush back 15 is provided with a seat abutment 20 and with a vertical screw opening 21. Inclined shoulders 23, 23 extend along the sides of the back 15 at the top edges and provide seat-contacting abutments.

The brush seat 10 is formed with downwardly and inwardly inclined shoulders 14, 14 along its sides which are adapted to support the brush shoulders 23, 23. The relationship is such that the brush seat below these shoulders may be eliminated, if desired, the bottom of the brush back being spaced from the bottom of the brush seat. At the inner end of the brush seat, which is open, the sloping face of the pulley 13 forms an overlying shoulder adapted to be contacted by the resilient pad 19.

The removable brush is shown positioned within the agitator in Figures 2 and 5. The end of the brush provided with the resilient pad or contact element 19 is extended under and into contact with the sloping end of the brush seat 10 formed by the agitator pulley 13. The sloping face of the end of the brush seat overlies the pad 19 and the resiliency of that member urges the brush inwardly and the brush shoulders 23, 23 against the seat shoulders 14, 14. At the opposite end of the brush seat the abutment 20 on the back is in contact with the face of the end of the seat 10 and a removable screw 22 extends through the opening 21 and into screw threaded relationship with the bottom of the seat.

To position the removable brush of the present invention in the agitator the resilient pad end of the brush is inserted under the sloping wall at the inner end of the brush seat 10 and the pad is compressed permitting the entrance of the opposite end of the rigid back of the brush into the seat. The screw 22 is then screwed into its seat

in the brush seat. The pad eliminates all relative vibration between the brush back and its seat and securely positions its end of the brush in place. The removal of the brush is simply the reverse operation.

I claim:

5. 1. In a suction cleaner agitator, a body having a brush seat, a brush comprising a rigid back and bristles, said back being positioned in said seat, part of said seat overlying said back, a resilient element carried by and removable with said back, said element contacting said overlying part and urging said brush into said seat, and manually operable means to lock said brush in said seat.
10. 2. In a suction cleaner agitator, a body having a brush seat, a brush comprising a rigid back and bristles, said back being positioned in said seat, a portion of said seat overlying said back, a rubber pad carried by and removable with said back, said pad being contacted and compressed by said overlying part and urging said brush into said agitator, and means securing said back to said seat at a point spaced from said pad.
15. 3. In a suction cleaner rotary agitator, a body having a brush seat formed with an overhanging inclined end, a brush comprising a rigid back and bristles, said back being seated in said seat, a resilient member carried by and removable with said back, said member being in contact with said inclined end and urging said brush therefrom, and manually operable locking means securing the opposite end of said back to said seat.
20. 4. A removable brush for a suction cleaner agitator comprising an elongated rigid back, bristles mounted therein and extended from the side thereof, and a resilient seat-contacting member on the bristle-side of said back.
25. 5. A removable brush for a suction cleaner agitator comprising an elongated rigid back, bristles mounted therein and extended from one side thereof, a recess in said back adjacent said bristles, and a block of resilient material seated in said recess.
30. 6. A removable brush for a suction cleaner agitator comprising an elongated rigid back, bristles mounted therein, a rubber block mounted at one end of said back, and means positively to lock

said back to a brush seat at the opposite end of said seat.

7. A removable brush for a suction cleaner agitator comprising an elongated rigid back, bristles mounted therein and extended at one side thereof, a rubber block mounted at one end of said back, and securing means at the opposite end of said back to secure said back to a brush seat.

8. In a suction cleaner agitator, a body formed with a brush seat, a brush seated in said seat and comprising a back and bristles, said back being formed with outwardly flaring shoulders on its sides in contact with said body to limit the extension of said back into said seat, and means urging said shoulders against said body.

9. In a suction cleaner agitator, a body formed with an agitating element seat, a surface-contacting agitating element in said seat and extended therefrom to a surface-contacting position, and shoulders along the sides of said element in contact with said body along the sides of said seat, and means to secure said element against outward displacement.

10. In a suction cleaner agitator, a body formed with an agitating element seat having outwardly facing shoulders along its sides and above its bottom, a surface-contacting agitating element in said seat and extended therefrom to a surface-contacting position, and body-contacting portions along the sides of said element so formed as to seat on said shoulders, and means to prevent outward displacement of said element from said body.

11. In a suction cleaner agitator, a body formed with an elongated agitating element seat having outwardly and upwardly inclined shoulders at its sides, a removable agitating element seated on said body and extended from within said seat to a surface-contacting position, said element being formed with inclined shoulders to rest upon the shoulders of said seat to support said element, and means to oppose separation of the shoulders on said back and on said seat.

12. A suction cleaner agitator element comprising an elongated body including a base portion, a surface-contacting portion, and shoulders at the sides of said element between the bottom of said base portion and the top of said surface-contacting portion.
